FUEL HEATER

Milton E. Chandler, Birmingham, Mich., assignor
to Bendix Aviation Corporation, South Bend,
Ind., a corporation of Delaware

Application April 7, 1932, Serial No. 603,877
Renewed December 24, 1937

5 Claims. (Cl. 123—122)

This invention relates to manifold heaters, and more particularly to a device for utilizing the heat of the exhaust gases of an internal combustion engine to heat the fuel mixture passing to the engine.

Heating of the fuel mixture passing to an internal combustion engine is advantageous when the engine is cold in order to promote the volatilization of the fuel and thus facilitate cold starting, but is disadvantageous after the engine has been warmed up, since the addition of heat beyond that necessary to smooth running decreases the volumetric efficiency of the engine. It is also desirable that the rate of heat transfer between the exhaust gases and the fuel mixture be varied as a function of engine speed, since even a cold engine will operate satisfactorily at high speeds under light load without heat being added to the fuel mixture, but will require more heat as the load increases and the engine speed decreases.

It is an object of the present invention to provide an improved intake manifold heater wherein the factors of temperature and engine speed are coordinated to control the rate of heat exchange between the exhaust and intake manifolds.

A further object of the invention is to provide an apparatus of the type indicated wherein the control is wholly automatic and wherein the construction is simple and inexpensive to manufacture.

Further objects and advantages of the invention will be apparent from the following description, taken in connection with the appended drawing, wherein the single figure is a view partly in section of a device embodying the invention.

Referring to the drawing, the reference numeral 10 designates the cylinder block of an internal combustion engine and 12 designates the exhaust manifold which is of special construction and which leads to an exhaust pipe 14. Located between the exhaust manifold 12 and pipe 14, and preferably formed integral with the exhaust manifold, is a section 16, of substantially rectangular cross section and constituting a casting for an unbalanced gate valve 18 which is fixed to a shaft 20 rotatably journaled in the casing.

Above the casing 16 and communicating therewith is a hollow member 22, preferably a casting, and constituting a heater or stove for the fuel mixture supplied by a carburetor 24, illustrated as of the downdraft, double-barrel type, although the invention is of course applicable to other types of carburetors. A gasket 26 of heat-insulating material may be interposed between the

carburetor and stove as shown. Flues 24 receive the fuel mixture from the carburetor and are preferably formed of thin sheets of copper or other material of high heat conductivity. Their lower ends are seated in parallel bores 5 formed in a member 27 which may be formed integral with member 22 and which has horizontal passages 28 leading to the intake manifold (not shown). The lower ends of the bores are closed by means of plates or domes 29 seated 10 therein and preferably formed of thin copper plates to facilitate the heat exchange. Flues 24 and member 27 are spaced from the inner walls of member 22 to permit the exhaust gases to circulate on all sides thereof. 15

Flanges 30 and 31 are formed in casing 16 in such relation to valve 18 that when valve 18 is held in the position indicated in full lines in the drawing the exhaust gases will be deflected by the valve and will pass upwardly around flues 24 and 20 downwardly to the left of flange 30 and valve 18 to the exhaust pipe 14. The valve and other parts are preferably streamlined to offer a smooth passageway to the exhaust gases.

A lever 33 is fixed to shaft 20 in such relation that it extends substantially horizontal when the valve is in its full line position, and carries at its outer end a weight 34, so that it tends to move valve 18 in the clockwise direction. A bimetallic element 35 in the form of a spiral spring has its 25 inner end fixed to shaft 20 and its outer end formed with a flange 36 designed to abut against an adjustable stop screw 38 which is threaded in a lug formed integral with the outer wall of the casing 16. 30

Element 35 is so constructed that it tends to coil more closely upon itself when heated and has an initial tension such that at ordinary atmospheric temperatures it urges valve 18 in the counterclockwise direction against the flange 36 with sufficient force to overcome the clockwise force of lever 33 and also the force of the exhaust gases, provided that the pressure of the exhaust gases against valve 18 is low. In this position of valve 18, the fuel mixture receives 40 the full heating effect of the exhaust gases. As the engine warms up, however, the temperature of element 35 rises and the force exerted by it decreases, leaving valve 18 free to oscillate under the influence of varying exhaust velocities, so that the heating effect on the fuel mixture is a function of engine speeds. At this stage, if the engine speed is low, the valve 18 may assume the intermediate position indicated at 18a, permitting a portion of the exhaust gases 45 50 55

to pass in heat-exchanging relation to domes 23 and then pass between the valve and flange 30 to the exhaust pipe. When the engine is fully warmed up element 35 has coiled upon itself to such an extent that it exerts no force on the shaft 20, leaving the position of valve 18 to be governed solely by the weight 34 and the pressure of the exhaust gases, whereupon it moves to the position indicated at 18b, in which position the exhaust gases pass directly to the exhaust pipe 14 without heating the fuel mixture.

Although the invention has been described with particular reference to a specific embodiment thereof, it may be embodied in other forms and is not intended to be limited except by the terms of the following claims.

I claim:

1. A fuel mixture heater for an internal combustion engine, comprising a path for exhaust gases in heat exchange relation to the fuel mixture passing to the engine, an exhaust pipe by-passing said path, a pressure-responsive valve controlling the flow through said path and said pipe, gravity means urging the valve toward one extreme position, and temperature-responsive means operative at low temperatures to urge the valve toward its opposite position.

2. In a device of the class described, means forming an exhaust passage, a valve in said passage, yielding means normally tending to open said valve, and a bi-metallic thermostat for closing said valve, said thermostat closing said valve against the force of said yielding means when the temperature is low, and having one end entirely free to move without interference by said valve or said yielding means whenever a predetermined temperature is exceeded.

3. In a device of the class described, means forming an exhaust passage, an eccentrically mounted valve for controlling passage of gas through said passage, passages for conveying gas

away from said passage at a point anterior to said valve and returning it to said passage at a point posterior to said valve, yielding means tending to hold said valve in open position, and a bi-metallic thermostat for closing said valve when the temperature is low, said thermostat being supported at one end only, and the other end of said thermostat being in operative relation to said valve mechanism only when the temperature is comparatively low.

4. In a device of the class described, means forming an exhaust passage, a butterfly valve mounted in said passage, a shaft for said valve, a bi-metallic thermostat carried by said shaft for operating it in one direction, and yielding means for operating said shaft in the other direction, said thermostat being located between said yielding means and the exhaust passage.

5. A fuel mixture heater for an internal combustion engine, comprising an exhaust passage, 20 a heating chamber designed to receive exhaust gases from the exhaust passage, a fuel mixture conduit extending into heat exchange relation to the heating chamber, a pressure responsive valve operative in one position to deflect the 25 exhaust gases from the exhaust passage into the heating chamber and operative in another, non-deflecting, position to form a partition between the exhaust passage and the heating chamber to exclude the gases therefrom, said valve 30 being unbalanced in such manner as to be urged at all times by the pressure of the exhaust gases toward the non-deflecting position, yielding means urging the valve toward the non-deflecting position, and temperature responsive means 35 operative at low temperatures to urge the valve toward the deflecting position and inoperative at all times to urge the valve toward the non-deflecting position.
